UNITED STATES PATENT OFFICE.

JOSEPH BAKOVICH, OF HERMONIE, PENNSYLVANIA.

SELF-LEVELING APPARATUS.

1,382,711.

Specification of Letters Patent. Patented June 28, 1921.

Application filed November 6, 1920. Serial No. 422,201.

To all whom it may concern:

Be it known that I, JOSEPH BAKOVICH, a subject of Jugo-Slavia, residing at Hermonie, in the county of Westmoreland and State of Pennsylvania, have invented certain new and useful Improvements in Self-Leveling Apparatus, of which the following is a specification.

This invention relates to balancing machines and the primary object thereof is to provide a leveling apparatus of the character described, in a manner as hereinafter set forth, whereby a supporting platform or table will be automatically maintained in perfectly level or horizontal plane. The device is primarily designed for use in connection with marine vessels for sustaining articles without overbalancing regardless of the pitching, rolling or lurching of the vessel. It will of course be understood that the principle of the device can be employed for any purposes wherein it is found applicable.

Further objects of the invention are to provide an apparatus of the class referred to which is simple in its construction and arrangement for the purpose intended, strong, durable and efficient in its use, readily installed, and comparatively inexpensive.

To the accomplishment of these and such other objects as may hereinafter appear, the invention consists of the novel construction, combination and arrangement of parts herein specifically described and illustrated in the accompanying drawings wherein is shown an embodiment of the invention, but it is to be understood, that changes, variations and modifications may be resorted to which come within the scope of the claims hereunto appended.

In the drawings forming a portion of this specification and wherein like numerals of reference designate corresponding parts throughout the several views:

Figure 1 is a top plan view of the base of the apparatus and mechanism mounted therein.

Fig. 2 is a side elevation thereof.

Fig. 3 is a side elevation of a leveling apparatus in accordance with the invention.

Fig. 4 is a top plan.

Fig. 5 is an end view.

Referring in detail to the drawings there is shown in Fig. 1 a rectangular base structure comprising the longitudinal side members 1 and 2 connected together by the trans-

verse end members 3 and 4. The end members 3 and 4 support a pair of parallel rails 5 and 6 forming a track upon which a wheeled operating truck 7 travels. The truck 7 carries a rack gear 8 positioned between the rails 5 and 6 and extending slightly above the top thereof.

A large operating gear 9, suitably journaled in bearing blocks 10 by the supporting shaft 11, meshes with the rack gear 8. Upon travel of the carriage or truck 7 in the longitudinal direction, the rack gear 8, carried thereby, will cause the rotation of the gear 9 in both directions, depending upon the direction of travel of the truck 7.

The shaft 11 carries a fixed bevel gear 12 which is in mesh with the bevel gear 13, which latter is carried by one end of the actuating screw 14. The screw 14 is journaled, as at 15, for rotation in the base structure and has threaded engagement with the block 16, mounted thereon.

Approximate the longitudinal center of each of the side members 1 and 2, is a vertical standard 17, the tops of which support an intermediate framing structure 18 pivotally connected thereto to permit a see-saw action of the structure 18 thereon.

A cable 19, passing over sheaves 20 and 21, connects one end of the intermediate framing structure 18 with one end of the block 16, while the cable 22, passing over sheaves 23 and 24, connects the other end of the structure 18 with the other end of the block 16.

The momentum of the carriage or truck 7 with its rack gear 8 in its travel will operate the gear mechanisms 9, 12 and 13, causing the rotation of the screw 14 and the longitudinal movement of the block 16 threaded thereon.

The longitudinal level of the intermediate framing structure 18 will be maintained at all times by the above described action of the device, for when the base structure is tilted due to the tossing of the vessel carrying same, the truck 7 will travel in the direction of the declination of the tilting movement, operating the screw 14 in the block 16, which latter draws the cable attached to the inclined end of the device, holding the intermediate structure 18 at a perfect level, due to its pivotal connection with the standards 17.

Mounted centrally on the intermediate framing structure 18 is a pair of transversely disposed rails 25 and 26, which forms a

track for a carriage or truck 27 provided with a rack gear 28. Structure 18 is further provided with a gear mechanism, screw, and block. The construction of the carriage 27, 5 rack gear 28, gear mechanism, screw and block supported by the structure 18 is identical to that carried by the base structure, but they are positioned to operate transversely instead of longitudinally with respect to the 10 device.

A pair of cables 29 and 30, passing respectively through sheaves 31, 32, 33 and 34, and through a common sheave 35, connects each 15 side of the framing structure 18 with respective ends of the block 36. Each end of the structure 18 is provided with a vertical standard 37, the tops of which carry a platform 38 pivotally connected, as at 39, thereto, allowing the lateral tilting movement of 20 the platform 38 in said connection.

It will be noted that the operating mechanism carried by the base structure will prevent longitudinal tilting only, of the structure carried by the standards 17, while the 25 mechanism carried by the intermediate framing structure 18 will prevent only the lateral tilting of the structure carried by the standards 37, but the combined operations of both mentioned mechanisms will automatically maintain the platform 38 in a 30 level position, and consequently the equilibrium of any article placed thereon.

To steady the movement of the trucks 7 and 27 during the operation of the device, 35 each of the trucks is provided with a pair of springs 54 and 55, the former connecting with the truck and one of the end members and the latter connecting the truck with the other of said end members. To entirely arrest 40 the operation of the device, a key 40 is inserted through the rails to engage the rack gears.

For the purpose of maintaining the shifting elements firmly against each other the 45 platform 38 has posts 41 on which pivots a frame 42 disposed parallel to the platform 38. Each corner of the platform 38 is provided with a bracket 43 carrying a pair of sprocket wheels 44 and 45 fixed on a common 50 shaft 46. A chain 47 attached to each corner of the frame 42 passes over the wheel 44, and a chain 48 attached to each corner of

the platform 49 passes over the sprocket 45. Each of the chains 47 and 48 is provided with a respective weight 51 and 52.

The frame 42, at each side thereof, has attached thereto a pair of brackets 56, each of which supports a rotatable sprocket 57, over which travels a chain 58. The latter carries on its lower end a weight, as indicated at 59. The upper end of each of the chains 58, is attached to a table 60, which shifts in a direction opposite the direction in which the platform 49 moves. The table 60 carries rollers 61 which travel on the 65 tracks 62 carried by the platform 49.

A breaking device for the elements of the structure and its operating means is indicated at 62'. The said operating means is so set up as to simultaneously operate all the 70 elements of the braking device.

What I claim is:—

1. A leveling mechanism comprising a base, an intermediate frame pivotally connected with the base, a platform pivotally connected with the frame, a gear mechanism carried by the base and having flexible connections with the ends of the frame, a gear mechanism carried by the frame and having flexible connections with the ends 75 of the platform, said gear mechanisms disposed at right angles to each other, and shiftable carriages carried by the base and frame for operating the gear mechanisms to balance the frame and platform.

2. A leveling mechanism comprising a base, an intermediate frame pivotally connected therewith, a platform pivotally connected with the frame, a gear mechanism carried by the base, a shiftable element operated by the gear mechanism and having flexible connections with the ends of the frame, a gear mechanism carried by the frame, a shiftable element operated by the gear mechanism on the frame and having 95 flexible connections with the ends of the platform, said elements disposed at right angles, and shiftable carriages mounted on the base and frame and operating the gear mechanisms to shift said elements for balancing the platform and frame.

In testimony whereof I affix my signature.

JOSEPH BAKOVICH.
